Primary Examiner — Paul D Bohannon(74) *Attorney, Agent, or Firm* — Bayramoglu Law Offices LLC(57) **CLAIM**

The ornamental design for a marine fishing chair, as shown and described.

DESCRIPTION

FIG. 1 is a front and top perspective view of a marine fishing chair showing my new design;

FIG. 2 is a front view thereof;

FIG. 3 is a rear view thereof;

FIG. 4 is a top view thereof;

FIG. 5 is a bottom view thereof;

FIG. 6 is a left side view thereof; a right side view being a mirror image of the left side view; and,

FIG. 7 is a rear and bottom perspective view thereof.

The broken lines shown in the drawings illustrate portions of the marine fishing chair that form no part of the claimed design.

1 Claim, 7 Drawing Sheets(56)
